UNITED STATES PATENT OFFICE

HARVEY CONOVER, OF CHICAGO, ILLINOIS

CHECK BOOK

Application filed October 1, 1928. Serial No. 309,624.

This invention relates to improvements in check books, and consists of the matters hereinafter described and more particularly pointed out in the appended claims.

5 The object of the invention is to provide a pocket check book including an attached blotter, which is of economical and simple construction and in which the blotter is so formed and connected to the body of checks 10 contained in the book, that each check, including the stubs, may be quickly and readily blotted in the process of unfolding and folding the book, when writing a check.

15 The advantages of the invention will appear more fully as I proceed with my specification.

In the drawings:—

Figure 1 is a view in perspective showing in full lines the improved check book opened 20 out in preparation to write a check, with the right-hand half of the book, shown in dotted lines, as it appears when approaching the folded condition in which it is ordinarily carried in the pocket, or in a folder of familiar 25 form.

Figure 2 is a perspective view of the book, with the blotter folded back in readiness for the inscription of the check stub.

Figure 3 is a side elevation of the book, 30 showing the position of the blotter in position to be applied to the stub; and Figure 3^a is a like view after the first check has been detached.

Figure 4 is a perspective view of the book 35 with the blotter in position to be applied to the written check.

Figure 5 is a fragmentary perspective view showing a modified construction of the blotter.

40 Figure 6 is a perspective view showing still another modified construction of the blotter.

Referring now to that embodiment of the invention illustrated in the drawings and particularly in Figures 1 to 4, inclusive:—

45 10 indicates a check book, which as to its general features, is of familiar construction, including a stack of checks 11 including stubs 12 with the usual lines of perforations dividing the checks and stubs, and with a binder 50 or back 14 to which the stack of checks is

stitched or stapled. The back as shown, is short, underlying only the stub part of the stack of checks and the book of checks as a body, is adapted to be folded back upon itself, as illustrated in dotted lines in Figure 55 1, to bring it to convenient size for carrying it in the pocket, or in a folder.

15 indicates a blotter. Said blotter is bound with the checks next adjacent to the face of the top check of the book. Said blotter is 60 as wide as the book of checks measuring from the top to the bottom of the check, and is twice as long as the stub 12. The blotter is so constructed that it may be folded on a transverse line 16 substantially midway between its ends. To this end, it may be creased or scored along said line, as shown in Figures 1 to 4, the particular method of providing for the fold, depending upon the character of the material forming the blotter. The fold 70 line 16 divides the blotter lengthwise into two sections 17, 18.

The checks are made of such length, compared to the length of the blotter when laid out flat its full length, that when the check 75 against the face of which it lies, or the check book as a whole, is folded back along the line at which the check book is designed to fold, the top face of the blotter will be substantially covered by that part of the top check or of the check book which lies beyond the end 19 of the blotter. To this end, the part of the check beyond the folding line of the book is made equal in length to the part of the check 80 including its stub, on the bound end part of the book.

The operation of the improved book is as follows. Normally and at first, before the first check has been written, the blotter lies flat against the top check, covering the stub and the top check up to the fold line of the book, as illustrated in Figure 1. When the first check is written, the blotter is folded upon itself to bring the one section 18 against the bottom side of its section 17 and then as a whole swung upon its line of connection to the binder 14 to the position indicated in Figure 2. As is usual in writing a check, the stub 12 is then inscribed. The folded blotter as a whole is then swung down upon the stub, 90 95 100

as illustrated in Figure 3, to bring the top face of the blotter section 18 into contact therewith, thus blotting the stub. The check itself is then inscribed. The blotter is now 5 unfolded to bring it to flat condition and is then swung down about the line of its binding with the back 14 with its bottom face in contact with the stub and with the part of the check on the left-hand side of the fold line 10 of the check book. The top check or the check book as a whole, is then folded back to bring the right-hand part of the face of the top check against the top face of the blotter, in the manner illustrated in Figure 4, thus blotting the right-hand part of the check. 15

The inscribed check is then detached along the line of perforation 13 from its stub 12. The blotter is then folded to bring the section 18 beneath the stub written, as shown in Figure 3^a. The check book is then ready for the writing and blotting of another stub and check. 20

While with suitable blotting material for the blotter 15 the blotter with a crease or 25 score may last the life of the book of checks without danger of severing the one section of the blotter from the other, it may be desired to reinforce the blotter along the fold line. In such case, the blotter may be constructed as shown in Figure 5. In this case like parts are indicated by the same numerals as used before with the superscript "a". 15^a indicates the blotter, which in this case is made in two separate sections 17^a, 18^a. Said 30 sections are connected by a flexible strip of suitable material 20 by means of which the blotter comprised of the two sections is made capable of folding along the line of junction. The operation is the same as in the other case. 35

In Figure 6 I have shown still another 40 form of construction of the blotter. In this case the two sections of the blotter 17^b, 18^b, are made duplex with an interposed strip of flexible material, such as paper or the 45 like, interposed between them and adhered to them by glue or other material of the kind. The outer sheet of blotting material may be scored and the inner sheet merely creased as shown in said view. This provides a very 50 efficient form of blotter in the use of which there is no strain on the blotting material itself (which is generally capable of resisting little strain of the kind) and at the same time a full blotting surface is presented 55 throughout the entire extent of the two blotter sections 17^b and 18^b on both faces.

While in describing the invention I have referred to several details of mechanical construction, it will be understood that the invention is in no way limited thereto, except as may be pointed out in the appended claim. 60

I claim as my invention:

65 A check book comprising a book of checks, including stubs, a blotter of the length of

said checks including their stubs, means for binding said blotter and checks at one end of the book, said blotter being in length substantially equal to half the length of the check including its stub, said blotter comprising two layers of blotting paper and an interposed strip of flexible material adhered thereto, one layer of said blotting material being scored and the other being creased on a transverse line substantially coincident with the line of detachment of the checks and stubs. 70

In testimony that I claim the foregoing as my invention, I affix my signature this 26th day of September, A. D. 1928. 75
